UNITED STATES PATENT OFFICE

HARRY B. CHALMERS, OF DEDHAM, MASSACHUSETTS.

AEROPLANE.

145,973.

Specification of Letters Patent. Patented July 13, 1915.

Application filed August 3, 1910. Serial No. 575,820.

To all whom it may concern:

Be it known that I, HARRY B. CHALMERS, a citizen of the United States, and a resident of Dedham, in the county of Norfolk and State of Massachusetts, United States of America, have invented certain new and useful Improvements in Aeroplanes, of which the foll wing is a specification.

My invention relates to improvements in aeroplanes, and its object is to improve upon apparatus of this kind, and to provide a simple construction arranged for a novel method of control which shall have advantages over such devices as have been hitherto known in the art.

I will describe my invention in the following specification and point out the novel features thereof in the appended claims.

Referring to the drawings, Figure 1 is a side elevation of an aeroplane made according to my invention. Fig. 2 is a front elevation of the same apparatus. In Fig. 3 I have shown the apparatus again in front elevation with some of its parts shown in different positions to illustrate one of its novl features of control. Fig. 4 is a plan view of the apparatus. Fig. 5 is a diagrammatic view of the device in front elevation. This figure illustrates the automatic balancing effect of the vertical plane.

Like characters of reference designate corresponding parts in all of the figures.

In the form of my invention which is shown more or less diagrammatically in the drawings there is a horizontal rectangular frame 10 upon which are supported the engine 20, the operator's seat 21, and the control handle 22. From the forward corners of the frame are two uprights 11 which are inclined backward and toward each other and are joined at their upper ends.

12 is a horizontal spar which is affixed to the uprights 11. Its outer ends are braced to the frame 10 by wires 13, and to the upper ends of the uprights 11 by wires 14. From these outer ends of the spar 12 rigid braces 15 run back to the rear bearing 23 of the shaft 24 of the propeller 25. The forward bearing 26 for this shaft is supported by a bracket which is also affixed to the braces 15. From the rear corners of the frame 10 are supports 16 which run up to and are affixed to the braces 15. The motor shaft is provided with an outboard bearing 27 which is connected with the frame 10

by braces 17, and with the bearing 23 by a strut 18.

The parts which have just been described form a rigid frame for supporting the other parts of the apparatus. The control handle, 60 the motor and its shaft, and the propeller and its shaft are the only movable parts which have been pointed out. These shafts are suitably connected by means of pulleys and a belt, or by means of sprockets and a 65 chain.

30 is an upper horizontal plane which comprises two or more longitudinal battens 31, all of which are affixed to the central cross-spar 12, and the ends of which are connected together by means of cross-battens 32. The frame thus formed may be braced and stiffened by means of wires in the usual manner, and then covered with cloth or other suitable material.

75 Wires 33 run from the end battens 32 up over pulleys 34 which are supported on the upper ends of the uprights 11, thence down under a pulley 35 back of seat 21 and to an arm 28 which is rigidly affixed to and depends from the post of the control handle which is supported at 29 with the frame 10 by means of a universal joint. It may be seen that by this arrangement a backward pull upon the control handle 22 will cause 80 the ends of the upper plane to be raised so that this plane will be bent into some such position as that indicated by dotted lines at 30^A in Fig. 1. Similar wires 36 from the forward cross-batten 32 to the arm 28, and wires 37 from the rear cross-battens 32 under a pulley 38 on the strut 18 to the post of the control handle 22 serve to pull the ends of the plane down into the position shown in dotted lines at 30^B when the handle 95 is pushed forward.

40 designates a flexible vertical plane which is supported and actuated by the parts which will now be described.

41 is a horizontal rod or stiff wire running between the longitudinal battens 31 near the forward end of the upper or horizontal plane.

42 is an arm the lower end of which is held fixed in relation to the upper plane by wires 105 43, but the upper end of which is arranged to slide laterally upon the rod 41. If desired a rod 44 (Fig. 1) may be run from the cross-spar 12 to the upper end of the arm 42. 45 is another arm at the rear end 110

of the machine, the lower end of which is pivoted to the strut 18 so that its upper end may have a lateral movement. An intermediate arm 46 is pivoted to the cross-spar 5 12 with its lower end so arranged that it may have a lateral movement. 47 is a tension spring which is connected to the lower end of this intermediate arm 46 with the lower ends of the arms 42 and 45 by means 10 of wires. A covering of textile or other material which has some resiliency is stretched over the frame thus formed. Its lower edge may be made with a hem to form a pocket within which lie the spring 47 15 and its connected wires. This forms the vertical plane 40. It is cut away as shown at 47 to clear the pulley on the propeller shaft.

50 designates wires from the lower end, 20 of the arm 46 which run over pulleys 51 on the uprights 11 and are affixed to the post of the control handle. These are so arranged that when the handle is pushed over to one side or the other the lower end 25 of the arm 46 will be moved in the opposite direction.

52 designates wires running from the lower end of the arm 46 over pulleys 53 on the side battens 31, and to the upper end 30 of the arm 42. These cause the movement of the lower end of arm 46 to be transmitted to the upper end of arm 42 but in the opposite direction.

54 designates wires running from the lower end of arm 46 over pulleys 55 on the braces 15, and to the upper end of the arm 45. These are so arranged that when the lower end of arm 46 is moved in one direction or the other the upper end of arm 45 40 will be moved thereby in the opposite direction.

From the above it may be seen that when the operator pushes the control handle 22 to one side, the lower end of the arm 46 will be moved over to the opposite side but the upper ends of the arms 42 and 45 will be moved to the same side as the control handle. The lower vertical plane will then assume some such position as that in which it is 45 shown in Fig. 3 and in dotted lines in Fig. 4 and designated by 40^a. Thus an apparatus is formed which comprises two planes at substantially right-angles to each other which are provided with means operable 50 from a single control handle for bending either or both of the planes. This bending of the planes is for the purpose of steering the apparatus vertically and horizontally. When the operator desires to go up he pulls 55 the control handle back, and when he desires to go down he pushes it forward. This 60 part of the operation in no way effects a lateral stability of the apparatus as do many of the devices in use in other machines of this character. Also, by the same control

handle, he may steer the machine to one side or the other by pushing the handle over to the side toward which he desires to turn. These operations may be performed independently or simultaneously. In the peculiar arrangement which I have provided for bending the vertical plane, lateral stability is maintained automatically as the burden of support is thrown upon the inner wing which counteracts the tendency of centrifugal force to upset the apparatus inwardly. The vertical plane prevents sidewise gliding which has previously prevented any considerable separation of the center of gravity and the center of upward thrust or 70 uplift.

In Fig. 5 the effect of the vertical plane to insure stability is shown diagrammatically. The forces produced by relative movement of the apparatus to the air 85 through which it is moving are represented by arrows, and the aeroplane is shown in a tilted position. It may be seen that fewer of these forces act on the high side of the apparatus, and that these have a tendency 90 to glide off. On the low side, however, more of these forces take effect and these have a maximum effect as they are pocketed and therefore have a strong tendency to 95 right the apparatus.

I have simply outlined the parts of this apparatus sufficiently to illustrate the principles which this invention involves, and to disclose enough structural parts to enable one skilled in the art to construct machines 100 embodying my invention.

What I claim is.—

1. An aeroplane having a vertical plane running through substantially the whole length of the apparatus and means for bending 105 said plane transversely throughout its length to guide the aeroplane horizontally.

2. An aeroplane having a vertical plane and means for moving both the upper forward portion and the upper rear portion of 110 said plane to one side and the lower central part thereof to the opposite side.

3. An aeroplane comprising a substantially horizontal main plane, a single vertical longitudinal plane below said main plane, and means for bending the vertical longitudinal plane to direct the movement of the aeroplane horizontally and for bending the entire main plane longitudinally throughout its length to guide the aeroplane 120 vertically.

4. An aeroplane comprising a main plane, a secondary plane depending at substantially right-angles from the central longitudinal axis of the main plane, and mechanism for bending the front and rear of the upper edge of said secondary plane to either side of said axis and the central part of the lower edge thereof in the opposite direction to the opposite side of said axis. 130

5. An aeroplane having a substantially horizontal main plane, means for bending said plane longitudinally throughout its length, a single centrally disposed vertical plane directly under said main plane, and means for bending said vertical plane longitudinally.

6. An aeroplane having a substantially horizontal main plane, means for bending said plane longitudinally throughout its length, a vertical single plane depending longitudinally from the central part of said main plane, and means for bending said vertical plane longitudinally throughout its length.

7. An aeroplane having a substantially horizontal main plane, means for bending said plane longitudinally throughout its length, a vertical plane, means for bending said vertical plane longitudinally, and a single control handle by means of which the bending of both of said planes may be accomplished.

8. An aeroplane having a substantially horizontal main plane, means for bending said plane longitudinally throughout its

length, a vertical plane depending longitudinally from the central part of said main plane, means for bending said vertical plane longitudinally throughout its length, a single control handle, a support therefor arranged to permit said handle to be moved back and forth and sidewise, and connections between the handle and the planes whereby the bending of both planes may be accomplished.

9. An aeroplane comprising a horizontal plane, a vertical stability plane of substantial proportions, connections to the central portion of said last plane whereby it may be rocked, and connections from said central portion to the upper ends of said plane whereby movements may be imparted to the upper forward and rear ends of said plane in the opposite direction.

In testimony whereof I have signed my name to this specification in the presence of two subscribing witnesses.

HARRY B. CHALMERS.
